United States Patent Office

Des. 185,082
Patented May 5, 1959

185,082

ROTATABLE SIGN

Howard T. Hutchens, Lakeland, Fla.

Application March 19, 1957, Serial No. 45,327

Term of patent 14 years

(Cl. D1—12)

FIG. 1

FIG. 2

Fig. 1 is a top perspective of a rotatable sign showing my new design; and

Fig. 2 is a side elevation thereof from the side opposite that of Fig. 1.

The broken line representation of letters in Fig. 1 is for purpose of illustration only.

I claim:

The ornamental design for a rotatable sign, as shown and described.
